US00D841663S

(12) **United States Design Patent** (10) Patent No.: **US D841,663 S**
Yuguchi et al. (45) Date of Patent: **** Feb. 26, 2019**

(54) **DISPLAY SCREEN WITH GRAPHICAL USER INTERFACE**

(71) Applicant: **Mitsubishi Electric Corporation**,
Tokyo (JP)

(72) Inventors: **Takashi Yuguchi**, Tokyo (JP); **Yotaro Fujimoto**, Tokyo (JP); **Nobuyoshi Kuwahara**, Tokyo (JP)

(73) Assignee: **Mitsubishi Electric Corporation**,
Tokyo (JP)

(**) Term: **15 Years**

(21) Appl. No.: **29/621,043**

(22) Filed: **Oct. 4, 2017**

(30) **Foreign Application Priority Data**

May 29, 2017 (JP) 2017-011414

(51) LOC (11) Cl. **14-04**

(52) U.S. Cl.

USPC **D14/485**

(58) **Field of Classification Search**

USPC **D14/485-495**

(57) **CLAIM**

The ornamental design for a display screen with graphical user interface, as shown and described.

DESCRIPTION

The FIGURE is a front view of a display screen with graphical user interface showing our new design. The outermost broken line showing a display screen and the broken lines showing elements of the graphical user interface illustrate portions of the article and do not form part of the claimed design.

1 Claim, 1 Drawing Sheet
